UNITED STATES PATENT OFFICE

136,096

DESIGN FOR A PAIR OF SPECTACLES

Austin B. Chaney, San Francisco, Calif., assignor
to American Optical Company, Southbridge,
Mass., a voluntary association of Massachu-
sets

Application November 24, 1941, Serial No. 104,271

Term of patent 14 years

To all whom it may concern:

Be it known that I, Austin B. Chaney, a citizen of the United States of America, residing at San Francisco, in the county of San Francisco and State of California, have invented a new, original, and ornamental Design for a Pair of Spectacles, of which the following is a specification, reference being made to the accompanying drawing, forming a part thereof.

Fig. 1 is a front elevation of a pair of spectacles showing my new design;

Fig. 2 is a fragmentary side elevation thereof;
and

Fig. 3 is a top plan view thereof.

My design for a pair of spectacles is characterized by the specific configuration of the lenses having the entire front contour bevelled, said bevelled edges being darkened by opaque material, in combination with long and slender bar-like temple supports so related with the lenses as to lie in the rear of the top bevelled opaque edge thereof, all as shown.

I claim:

The ornamental design for a pair of spectacles, substantially as shown and described.

AUSTIN B. CHANEY.
